J. W. HOWE AND J. K. BARTON, OF WORCESTER, MASSACHUSETTS.

Letters Patent No. 71,881, dated December 10, 1867.

CORN-POPPER.

The Schedule referred to in these Letters Patent and making part of the same.

KNOW ALL MEN BY THESE PRESENTS:

That we, J. W. HOWE and J. K. BARTON, of the city and county of Worcester, and Commonwealth of Massachusetts, have invented certain new and useful Improvements in Corn-Poppers; and we do hereby declare that the following is a full, clear, and exact description of the same, reference being had to the accompanying drawings, forming a part of this specification, in which—

Figure 1 represents a view of the bottom, rear, and one side of the popper, and

Figure 2 represents a rear view of the popper, and a part of the metal handle, as will be more fully explained hereafter.

To enable those skilled in the art to which our invention belongs to make and use the same, we will proceed to describe it more in detail.

In the drawings, the part marked A represents the corn-receptacle, made of wire cloth, and B a section of the wooden handle, which has heretofore been usually fastened to the rear part C, by means of two pieces of strap-iron; one end of one piece being fastened to the upper side of the handle, and then extended over the top of the receptacle, and bent down upon the inside, to be fastened by a rivet to the bent end of the other piece, which is fastened to the under side of the handle. When the handle is thus fastened, the receptacle is not supported in a proper manner, while the connection is very liable to give out, and frequently the wire cloth is broken by the rivet which fastens the ends of the metal straps to the rear of the receptacle A.

To obviate the foregoing and other objections, we fasten the wooden handle B to the receptacle A, by means of four wires $a a' a' a'$. The wires $a a$ are made or bent to fit the rear and bottom of the receptacle A, while their front ends are bent up and clinched or hooked into the wire cloth forming the front of the receptacle. The wires $a' a'$ are bent to the right and left, and their ends $b b$ passed through holes in the metal binding D of the receptacle A, and then up through holes in the metal binding E of the cover, after which they are turned or bent down in hook-form, as fully shown in the drawings. The rear ends of all the wires are twisted together, as shown at F, and which wires, when so twisted together, may be driven into the end of the wooden handle B, or they may be extended to such length as to form a metal handle. We prefer, however, to extend them only to such a length as to form a suitable shank, the end of which is to be driven into the wooden handle B, as indicated in the drawings. By our improvements, a strong handle is formed, while two of the wires $a a$, which form a part of the handle, are made to diverge and pass under the receptacle, as shown at $a c$, and thus form protectors to the wire cloth when the receptacle is set upon a stove. The ends of the other two wires $a' a'$, while they hold the rear of the receptacle securely in place, also serve as hinges to the cover. It will be observed that the wires $a a' a' a'$ are made to form the connection between the receptacle A and handle B, while the two former are made to answer as stays to the back and front of the receptacle A, and also as protectors to the bottom of the popper, and the two latter wires $a' a'$ are made to answer as strong supports to the rear of the receptacle A, and also as hinges to the cover. Again, it will be noticed that the connection of the handle with the popper is such that there is not that constant strain and great wear upon the wire cloth, which is the case when the handle is fastened to the popper in the usual manner. Our improvements are alike applicable to round poppers.

Having described our improvements in corn-poppers, what we claim therein as new, and of our invention, and desire to secure by Letters Patent, is—

1. The combination of the twisted wires $a a' a'$, with the handle B, and receptacle A, substantially as and for the purposes described.
2. The combination of the wires $a' a'$, with handle B, receptacle A, and cover of the same, as and for the purposes described.
3. The combination of the wires $a a' a' a'$ with each other, receptacle A, and cover of same, as shown and described.

J. W. HOWE,
J. K. BARTON.
